DISPENSING DEVICE

Ralph R. Cone, Glen Ellyn, Ill.

Application September 15, 1933, Serial No. 689,623

11 Claims. (Cl. 120—69)

The present invention relates to a device for dispensing liquids, particularly where it is desired to raise the liquid in a container of the type employed for inks, medicines, etc.

Whereas there are numerous prior disclosures of devices intended for the same general purpose, there has heretofore been no commercial recognition of a device for the purpose because of expense in manufacture, complexity of design and unsatisfactory operation in practice.

In some cases these prior devices for raising liquid levels have consisted of a container provided internally with an integral level raising well which is obviously costly to manufacture and is not susceptible to use with containers already on the market. Other devices have been proposed in which a separate level raising well is inserted into the mouth of its container, but these wells have slots provided in their side walls, rendering it impossible to bring the liquid close to the top of the container and thus, by their design, defeat the primary purpose for which they were intended.

The desirability of an efficient device for raising the level of ink in a bottle, for example, is evidenced by these unsuccessful attempts in the past to provide an arrangement whereby a pen might be dipped into or filled from the original container without soiling the portion of the pen which is grasped when in use for writing. It is the object of the present invention to overcome these faults and difficulties which are prevalent in the prior art and fulfill the requirements of the trade with a device which is simple and compact, inexpensive to manufacture and convenient to operate. The invention distinguishes, for example, over patents such as those to Gosselin No. 1,273,479 dated July 23, 1918 and Hauser No. 1,896,405 dated February 7, 1933.

The present invention is applicable to existing containers and contemplates an auxiliary container or liquid level raising well which frictionally engages the internal wall of the principal container for rigid support. A chambered closure is provided for the principal container to which chamber the liquid has access around the body of the well upon inversion of the assembled unit. The wells are preferably constructed so that they may be nested during manufacture and prior to their insertion into the container, and so that they will operate efficiently with very small quantities of liquid present in the container.

In the drawing,

Fig. 1 is a sectional elevation of the assembled device;

Fig. 2 is a perspective of a form of the auxiliary container;

Fig. 3 is a plan of the auxiliary container; Fig. 4 is a section through 4—4 of Fig. 2; and Fig. 5 is a modification.

Referring to the drawing in detail, 10 represents an ink bottle of the usual type having a reduced neck 11 and an inner wall 12. A closure 13, provided with fastening means such as screw threads 14, engages with cooperating means such as screw threads 15 provided on the neck of the bottle. For the reception of ink when the bottle is inverted, the closure is provided with a chamber 16. A flange 17 may be formed internally of the closure for reception of a gasket 18 of any suitable material for binding engagement with the rim 19 of the bottle.

Received within the neck of the bottle is an auxiliary container or level raising well 20 whose inner and outer walls 21 and 22 respectively are preferably tapered to the same degree, forming in effect a frusto-conical member closed at its smaller base. The outer wall 22 is provided with a flanged portion 23 which may have a rounded lower edge, Fig. 2, or a more abrupt shoulder, Fig. 5, which flanged portion is continued to the larger base of the frusto-conical member to constitute a rim 24. The flange 23 is provided with cut-out portions 25 which may conveniently assume the form of fluting.

As shown in Figs. 1 to 4, the outer periphery 26 of the flange 23 is substantially cylindrical while in the modification in Fig. 5 it is designated as 26' and shown as slightly tapering or frusto-conical. In this manner when the well is applied to an existing container or bottle whose inner wall is tapered or provided with a bulge, the form in Fig. 1 might be conveniently employed, while in a container or bottle having a cylindrical bore the form in Fig. 5 would be preferred.

Due to the fluting provided in the flange, the rim of the well will present a thin surface of material making the well susceptible to flexibility in the neighborhood of the rim so that a forced fit in the bottle may readily be achieved.

It is clear that during manufacture of the auxiliary containers, they may be nested together for operating upon several of them at the same time. This possibility of nesting may find additional importance for purposes of storage and shipping.

A variety of materials may be employed for fabricating the auxiliary container among which might be mentioned wood, cork, paper, rubber, metal, celluloid, cellophane, pressed compositions or compositions impervious to the chemicals pres-

ent in the liquid to be dispensed. It is also contemplated to make the flange portion a separate member under which conditions the auxiliary container may be composite and constructed of different materials. In a like manner the closure element may be made of a variety of materials and may also be composite.

In operation, assuming a liquid level in the bottle at the height indicated at 27, the bottle is slowly inverted so that the liquid passes between the outer wall 22 of the auxiliary container and the inner wall 12 of the principal container through the passages or flutes 25 into the chamber 16 provided in the closure element. The bottle is then quickly righted to assume its normal position whereupon the liquid will pass from the chamber into the auxiliary container, establishing a liquid level therein which is only slightly below the rim of the bottle. This distance is only sufficient to prevent an overflow of liquid from the bottle itself. It will be obvious that the chamber in the closure must have a content equal to or greater than the content of the well in order to assure complete filling of the latter.

It is contemplated that suitable fluting might be formed in the container itself, in which event the well or its flange need not be fluted. It is also intended that the invention be adapted to containers of any sectional form, with or without reduced portions, and that the section of the well be made in any efficient form and not necessarily frusto-conical.

This invention is not to be restricted to shapes or materials except as specified in the appended claims.

I claim:

1. A dispensing device comprising a container having a rim and an opening, an auxiliary container having a rim and having a discontinuous flange in positive engagement with the inner wall of the first named container, said rims defining a volume therebetween less than that of the auxiliary container and a chambered closure for said containers which defines with the rim of the auxiliary container, a volume as great as the capacity of said auxiliary container.

2. A dispensing device comprising a container having an opening, an insertable auxiliary container disposed within and in positive wedged engagement with, the inner wall of the first said container, a passage between the inner wall of the first said container and said auxiliary container, and a chambered closure for said containers having a capacity substantially equal to that of said auxiliary container.

3. A dispensing device comprising a container having a rim, an auxiliary container positively engaging the inner wall of the first said container, said auxiliary container having an opening defining a rim but having imperforate walls, one of said walls having a passage formed therein, the planes of said rims being so spaced that the volume included therebetween is less than that of the auxiliary container.

4. A dispensing device comprising a bottle having a reduced neck terminating in a rim, an auxiliary container having an imperforate wall terminating in a rim, said auxiliary container having a portion of its outer wall in wedged relation with the inner wall of said reduced neck so as to

permit fluid passage between said walls, the rim of said auxiliary container being disposed slightly below the rim of said bottle, said rims defining a volume less than that of the auxiliary container.

5. A dispensing device comprising a bottle having a reduced neck terminating in a rim, an auxiliary container having an imperforate wall terminating in a yieldable rim, a discontinuous flange provided on the outer wall of said auxiliary container having its upper surface substantially coplanar with the rim, said flange frictionally engaging the inner wall of said reduced neck, the rim of said auxiliary container being disposed slightly below the rim of said bottle, the volume included between said rims being less than that of the auxiliary container.

6. A dispensing device comprising an auxiliary container having inner and outer walls terminated to form a closed base and a rim, substantially defining a hollow frustum of a cone, and a discontinuous flange carried by the outer wall of said container, the outer dimension of said base being sufficiently smaller than the inner dimension of said rim to permit a substantial telescoping upon nesting a pair of such auxiliary containers.

7. A dispensing device comprising an auxiliary container having inner and outer walls of substantially equal taper through a major portion of their length, terminated to form a base and a rim, a discontinuous flange in rigid relation with said outer wall, the outside dimension of said base being inferior to the inside dimension of said rim.

8. A dispensing device comprising an auxiliary container capable of nested relation with its counterpart, having inner and outer walls terminating in a rim and a discontinuous flange on said outer wall terminating at said rim.

9. A dispensing device comprising an auxiliary container having inner and outer walls of substantially equal taper for substantially their full length, terminated to form a rim, an integral discontinuous flange formed on said outer wall, said outer wall having a minimum section substantially less than the maximum section of said inner wall.

10. A dispensing device comprising a container having a rim, an open auxiliary container having imperforate walls frictionally suspended in said container and defining a passage therewith, said auxiliary container having a substantially frusto-conical external flange near the container rim and said rims defining a volume less than the capacity of the auxiliary container.

11. A dispensing device comprising a container having its walls terminated in a rim, an auxiliary container positively engaging the inner wall of said container, said auxiliary container having imperforate walls terminated in a rim, said rims defining a volume therebetween less than that of the auxiliary container, a chambered closure for said containers which defines with the rim of the auxiliary container, a volume as great as that of the auxiliary container, and the device being provided with a passage interconnecting the chamber of the closure and the first said container.
